(Cl. D55—1)

FIG. 1

FIG. 2

FIG. 3

FIG. 4

FIG. 5

FIG. 1 is a front elevational view of a mixer plow showing my new ornamental design;

FIG. 2 is a top plan view of the mixer plow of FIG. 1;

FIG. 3 is a side elevational view of the mixer plow of FIG. 1;

FIG. 4 is an opposite side elevational view of the mixer plow of FIG. 1; and

FIG. 5 is a rear elevational view of the mixer plow of FIG. 1.

The essential features of the design reside in the portions shown in full lines on the drawings.

The arm member is shown broken away in FIGS. 1, 3, 4 and 5 to indicate indeterminate length.

I claim:

The ornamental design for a mixer plow, substantially as shown and described.
